ELEVATOR DOOR OR GATE OPERATING
MECHANISM

Clarence O. Harmon, Detroit, Mich.

Application May 4, 1948, Serial No. 24,933

10 Claims. (Cl. 187—52)

1

This invention relates to operating mechanism for elevator doors or gates. It can be used for raising or lowering the doors or gates of freight elevators and it can also be used for operating the horizontally sliding doors of other elevators, such as passenger elevators.

In operating freight elevators it is the customary practice to have the doors or gates operated by a motor or motors located on each floor. Usually there are two motors, one on each side of the shaft, which by suitable driving connections, such as sheaves or sprocket wheels and cables or chains, raise and lower the doors or gates when these motors are energized by switch mechanism operated on the elevator.

It is the object of the present invention to eliminate the necessity of motors on each floor to operate the gates.

It is not broadly new to use a motor on the elevator to connect with operating mechanism on each floor to operate the gates or doors when an elevator arrives at a floor, but so far as known, none of these arrangements has been successful for the operation of vertical sliding doors or gates. There are many difficulties inherent in making a satisfactory connection between the driving mechanism on the elevator and the driven mechanism on the wall of the building. One of these difficulties is that all elevators sway and attempts to use operating connection, such as sprocket wheels which are brought into engagement with a chain, have been unsuccessful because this swaying makes it impossible to make a reliable connection. If a driving connection is established in such mechanism the connection is a positive one, and if resistance is met in the opening and closing of the doors or gates the mechanism will be damaged if the resistance is too great or if a person gets caught between the gates he will suffer serious injury by reason of the positive drive from the motor to the gates.

It is the object of the invention to provide a drive on the elevator which can dependably couple up with the driven mechanism on each floor and which will obviate the difficulties and deficiencies heretofore found in apparatus of this kind.

Referring to the drawings:

Fig. 1 is an elevation showing elevator doors or gates operated by a motor on the top of a freight elevator.

Fig. 2 is an enlarged elevational view taken on the line 2—2 of Fig. 1.

Fig. 3 is a plan view partly in section taken on the line 3—3 of Fig. 2.

Fig. 4 is a fragmentary elevation of the driving

and driven connections shown in Fig. 3 showing the position of the driving element slightly different from that shown in Fig. 3 due to the sway of the elevator.

5 Fig. 5 is an elevational view of a modified form of the invention applied to an elevator with a horizontally sliding door.

Fig. 6 is an elevation taken on the line 6—6 of Fig. 5.

10 Fig. 7 is an elevation of another modification which, however, is the preferred form of the invention.

Referring to Fig. 1, 1 is a freight elevator with the usual vertically sliding gates 2 and 3. These doors or gates are connected by the chains 4 and the rods 5. The chains pass over sprockets 6. The doors counterbalance one another.

The driven mechanism for raising or lowering the doors comprises a chain 7, a sprocket wheel 8, a pair of spur gears 9 and 10 and a driven friction roll 11. The driving mechanism is shown in detail in Fig. 2. A large driving friction roll 12 is journaled at 13 on the bracket 14 on motor-carrying arm 15. Attached to this arm is a solenoid armature 16. Solenoid 17 is contained in a housing 18 located on the top 19 of the elevator. The motor housing is pivoted at 20 to this housing. The solenoid housing 18 and motor housing are supported on a base 21 which can be adjusted along the top of the elevator to determine the amount of load or pressure of the driven roll 12 on the driven friction roll 11. The further to the right that the base 21 is adjusted the greater will be the angle of a line through the journal 13 of the driven roll 12 and pivot 20 and a vertical line through the pivot 20. The greater that angle the greater the moment of the load of the driving mechanism on the driven mechanism and the better the traction. Hence, it is possible to determine by the adjustment of this base the amount of resistance which will cause the rolls to slip. The greater the angle of the driving roll shaft from the vertical line through the pivot 20 the greater resistance it will be able to overcome before the driven rolls slip.

40 As long as the elevator driving motor is energized solenoid 17 is energized because the circuit 22 connects through wires 23 to the main motor circuit of the elevator. Hence, when the controller on the elevator is swung to operating position solenoid 17 is energized and draws the armature 16 in and swings the driving roll 12 away from the driven roll 11.

45 When the car arrives at a floor the operator 50 throws off the control switch which controls the

55

circuit for the elevator motor and also the solenoid. The driving roll drops down on the driven roll, then a push-button switch on the car is closed and the circuit 24 which leads to the motor A is completed. This causes the motor to rotate the driving roll 12 to drive driven roll 11 which in turn, through the spur gears 9 and 10, operates the sprocket 8 and the chain 7 which pulls the doors open. There will be a limit switch (not shown) which will break the circuit when the doors reach a fully open position.

When the operator desires to start the car again he must first close the doors by pushing on another button which sends the current in a reverse direction through the motor and causes the motor and the friction wheels to rotate in the opposite direction and thereby cause the chain 7 to move in the opposite direction and close the doors. A limit switch (not shown) will break this circuit when the doors reach closed position. When the doors reach closed position they will re-establish the circuit to the elevator motor (not shown) which has been broken when the doors or gates begin to open. This is the common arrangement.

Figs. 5 and 6 show my invention used in connection with a horizontally sliding door or doors. Here in Fig. 5 only one driving mechanism is shown for operating one door 26. A chain 27 is fastened to the top of the door at 28. The door has rollers 29 which travel on track 30. Chain 27 is driven by sprocket 31 which is on end of shaft 32. A pair of bevel gears 33 are used to couple shafts 32 and 34 in driving relation. Shaft 34 is driven by gear 35 in mesh with gear 36 on the driven roll shaft. The driven roll 11 is driven by the large driving roll 12. The driving mechanism is exactly the same as already described and no further description is necessary.

Referring to Figs. 3 and 4, it will be seen that the driven roll is a rubber roll while the driving roll is a steel roll. The drive is entirely by friction. If the load to be moved is too great the rolls will slip instead of drive. For instance, it usually takes somewhere from 30 to 50 pounds to move the vertically moving elevator gates or doors. These gates are counter-balanced one against the other. All the power that is required to move the gates is what is necessary to overcome the friction in the guides and actuating mechanism. There is considerable gear reduction from the motor through the large driven gear 37 and the small motor-operated driving gear 38, through the spur gears 9 and 10 and the chain sprocket 8. The angle that the driving roll shaft is to a vertical line through the pivot on which the motor housing (the roll-carrying arm) swings determines the amount of traction of the two friction rolls. As already explained, the greater the angle the greater the amount of the load of the driving roll, the motor-carrying arm 15 and the motor A, and hence the greater pressure between the two rolls. The unit carrying the motor and the driving roll can be adjusted along the top of the elevator to get such a moment or load of the driving roll pressing on the driven roll as to make sure that the rolls have a sufficient traction to operate the doors under all normal conditions. But preferably the margin of friction or the traction will be sufficient only to insure such operation with no abnormal resistance. If the load on the mechanism becomes too great by reason of some obstruction against the doors or a person getting

caught between the doors, then with this small margin of traction slippage will take place. Hence with any obstruction the door mechanism will stop driving and therefore save the operating mechanism from serious injury or save a person or some other object from serious harm.

Another feature of the improvement is shown in Figs. 3 and 4. Note how the places of contact between the driving and driven roll may change. The driven roll can be made, say six inches or more long. This allows a considerable surface lengthwise along the roll in which the driving roll 12 may contact. In Fig. 3 the contact is almost in the middle of both rolls. In Fig. 4 the contact is not in a full contact and is out at the end of the driven roll. This is a desirable feature for it insures the contact and the rolls coming together in driving relation when the larger roll is dropped onto the smaller roll. This is not possible where it is proposed to drop onto the driving chain for the doors a sprocket wheel mounted on the elevator. As there is considerable sway in most elevators, hence the sprocket wheel may or may not catch in the chain so apparatus of this kind cannot be depended upon for satisfactory operation. Of course, other forms of friction drive could be used so when driving and driven rolls are recited in the claims it should be understood that these other equivalent friction drives are covered.

Another feature of my apparatus is the effort required to move the elevator doors on different floors may vary. It is, therefore, possible on different floors to use a different gear reduction between the driven roll and the lifting chain to provide about the same safety margin of driving effort over operating load. By driving effort is meant the maximum traction before slippage of the rolls which provides the safety factor which is believed to be new in a door actuating connection between mechanism on the elevator and mechanism located on the wall of the building.

The preferred form of the invention is shown in Fig. 7. Here the arm or motor housing 39 has its center of gravity to the right of shaft 40 so that the driving wheel 12 is normally maintained out of contact with the driven roll 11 which drives sprocket 8 and chain 7. A torque motor B has a reduction gearing connection 42 with pulley wheel 43. This pulley wheel 43 has two grooves, one in which the chain 44 rests and in the other the chain 45. Chain 44 is connected to the retiring cam which releases the door interlock (not shown). The other chain 45 is connected to lever arm 46 which is connected by shaft 40 with the motor-carrying arm 39. This lever arm is counterweighted by counterweights 47 and its range of movement is controlled by set screws 48 and 49.

The amount of pressure of the driving roll upon the driven roll may be varied by altering the torque of the torque motor. This can be done by introducing different amount of resistance into the torque motor circuit by well-known resistance inserts. This torque and pressure will determine the margin of tractive effort over normal load.

The operation is as follows: When the elevator is at rest at a floor, the torque motor can be energized through the circuit 52 by a push button (indicated in Fig. 7) in the car. This will energize the circuit 50 leading to the torque motor B provided, however, the car is at rest at a floor, and the automatic switching mechanism (not shown) in the controller has closed the circuit through

the controller. The same circuits and push button furnish current to circuit 53 leading to motor A to drive the driving roll 12, which in turn drives the driven roll 11, and causes the movement of the chain 7 to operate the vertically sliding doors, as has already been described in connection with Fig. 1. However, as stated below, circuit 54 has to be closed before circuit 53 to motor 15 is closed. When the doors close a limit switch (not shown) will automatically discontinue the motor energization and also close the switch to the elevator motor so that the elevator may be made to move up or down by operation of the controller on the elevator.

When the push button switch in the car is released or the limit switch opens the circuit 53, the circuit 58 to the torque motor B is also broken and the driving motor A and the driving roll is returned to the idle vertical position by gravity. Hence, the driven mechanism is out of contact with the driven roll and there will be no abrasion of the rubber driving roll by reason of the swaying of the elevator. In this respect this torque motor arrangement is an improvement over the gravity driving arrangement used in the other modification of the invention, shown in Figs. 1, 2, 5 and 6, because in this modification (Figs. 1, 2, 5 and 6) the driving rolls are in contact at all times while the car is at rest and the solenoid circuit is de-energized. This arrangement of Fig. 7 requires less current as the current is only on when the doors are being closed or opened.

As stated above, circuit 54 has to be closed before the push button will be effective to energize circuit 53 to the motor A. This circuit 54 leads to the retiring cam that controls the elevator door interlock. This door interlock has to be released before the driving motor A can be energized.

We have not attempted to show these circuits and switches in detail as such circuits are well known in the elevator art and they are no part of my invention.

I claim:

1. Actuating mechanism for the gates or door guarding the opening into an elevator shaft at each floor of a building, having in combination a driving unit on the elevator having a friction driving roll supported on a pivoted arm which in turn is supported on a base adjustable laterally of the elevator to change the angle of the arm to the vertical and hence the moment of the driving roll at the limit of the downward movement of the arm, a driven friction roll for location on the building and on which the driving roll rests when the arm is dropped in tractive but slipping relation under an overload, driven operating connections for location on the building and for the elevator door or doors coupled with the driven friction roll, and means for keeping the arm raised except when it is desired to drop the driving roll on the driven roll preparatory to operating the door or doors.

2. The combination claimed in claim 9 in which the driven operating connections include reduction gearing in which the gear ratio may be varied

to meet the load furnished by the door or doors on each floor.

3. The combination claimed in claim 9 in which the friction rolls have sufficient width to vary the contact zone between the rolls and allow for swaying of the elevator.

4. The combination claimed in claim 9 in which one or more of the friction rolls has a periphery of material with a high coefficient of friction, such as rubber.

5. The combination claimed in claim 9 in which the means for keeping the arm raised is a solenoid.

6. The combination claimed in claim 9 in which the means for keeping the rolls disengaged is gravity and the means for bringing the driving roll into contact with the driven roll is a torque motor.

7. The combination claimed in claim 9 in which the means for bringing the driving roll into contact with the driven roll is a torque motor.

8. The combination claimed in claim 9 in which the means for bringing the driving roll into engagement with the driven roll is a torque motor with a circuit in which a variable resistable element may be inserted to vary the margin of tractive effort over the normal load.

9. Actuating mechanism for the gates or doors guarding the opening into the elevator shaft at each floor of a building, having in combination a motor operated driving unit on the elevator having a movable member journaling a friction driving roll, said journaling member arranged to be normally positioned to have the driving roll out of driving position, a base for supporting the said journaling member movably on the elevator, a driven roll for journaling on the building at or adjacent the elevator shaft, transmission connections for location between the friction driven roll and the gate on the building for moving the gate in opposite directions with the rotation of the driven roll, electrically controlled means for bringing the driving roll into friction driving contact with the driven roll, and power means for rotating the driving roll to thereby counter rotate the driven roll and thereby cause the transmission connections to open or close the gate.

10. The combination claimed in claim 9 in which the means for bringing the driving roll into contact with the driven roll is a torque motor, a pulley wheel and draft members which both go over the pull wheel, one to release the latch on the gates and the other to move the journaling member to bring the drive and driven roll into frictional driving contact.
